CLAIM

The ornamental design for a dispensing box for denture cleansing tablets, as shown and described.

DESCRIPTION

FIG. 1 is a front perspective view of a dispensing box for denture cleansing tablets, showing my new design;
FIG. 2 is a side elevational view thereof;
FIG. 3 is a top plan view thereof;
FIG. 4 is a bottom plan view thereof;
FIG. 5 is a bottom, front perspective view thereof.
The rear of the box is flat and unornamented.

FIG. 1

FIG. 2

FIG. 3

FIG. 4

FIG. 5
